No. 731,859.

PATENTED JUNE 23, 1903.

W. R. CLARK.
COMBINATION TOOL.

APPLICATION FILED JULY 13, 1901.

NO MODEL.

UNITED STATES PATENT OFFICE.

WILLIAM R. CLARK, OF TEHACHAPI, CALIFORNIA.

COMBINATION-TOOL.

SPECIFICATION forming part of Letters Patent No. 731,859, dated June 23, 1903.

Application filed July 13, 1901. Serial No. 68,223. (No model.)

To all whom it may concern:

Be it known that I, WILLIAM R. CLARK, a citizen of the United States, residing at Tehachapi, in the county of Kern and State of California, have invented a new and useful Combination-Tool, of which the following is a specification.

This invention is a combination-tool, the object being to provide a tool embodying a variety of different articles and one which shall be exceedingly cheap and simple in construction and thoroughly efficient in operation.

With these objects in view the invention consists in the peculiar construction of the various parts and in their novel combination or arrangement, all of which will be fully described hereinafter and pointed out in the claim.

In the drawings forming part of this specification, Figure 1 is a perspective view of a combination-tool constructed in accordance with my invention. Fig. 2 is a plan view of the same. Fig. 3 is an edge view. Fig. 4 is a detail view showing the jaws open. Fig. 5 is a view showing the jaws closed, said view being taken from the side opposite to that shown in Fig. 2. Fig. 6 is a section on the line 6 6 of Fig. 3. Fig. 7 is a section on the line 7 7 of Fig. 2.

In carrying out my invention I employ two jaws A and B, pivotally connected by means of a bolt or rivet C. The ends of the jaws A and B are formed into nippers A' and B', respectively, and wire-cutting notches A² and B² are formed adjacent to the inner ends of the nipper-points for the purpose of cutting wire. The rear portion of the jaw A is in the form of an open frame, a portion thereof being turned back and sharpened, as shown at A³, to provide a can-opener, and the extreme end is shaped to produce a screw-driver A⁴. Scale-marks A⁵ are produced upon one mem-

ber, and a notch A⁶ is produced adjacent the can-opener to be used as a spoke-wrench. 45 The open-frame portion of the jaw A can be used as a wrench for various-sized nuts. The end of the jaw B is curved or pointed, as shown at B³, said curved and pointed end serving at one time as a cork-extractor and 50 another as one leg of a caliper. The point A⁷ upon the jaw A serves as the other point of said caliper. A circular opening B⁴ is produced in the jaw B, the edges being beveled, as shown, thereby providing a convenient pencil-sharpener. The edge of the jaw B⁵ is also sharpened and adapted to form one member of a pair of shears, the sharpened edge A⁸ of the jaw A forming the other member. The edge B⁶ does not meet the opposite 60 side of the jaw A, thereby forming a slot B⁶ in which the shank of a button can be placed while the button is being polished.

It will thus be seen that I provide a combination-tool embodying a number of different implements all combined and arranged for convenient operation and so located and arranged that one part will not interfere with the operation of another part.

Having thus fully described my invention, 70 what I claim as new, and desire to secure by Letters Patent, is—

A wrench, one member of which is a triangular-shaped frame, a second irregular-shaped member pivoted to the first member adjacent 75 its narrowest portion, the said second member having its widest portion at said pivotal point, and being notched adjacent said point and tapered at its adjacent end, said tapered portion and the narrow portion of the first- 80 named member being adapted to serve as gripping-jaws.

WILLIAM R. CLARK.
